UNITED STATES PATENT OFFICE.

GEORGE L. COWPERTHWAIT, OF CLARKS SUMMIT, PENNSYLVANIA.

LOCKING BAR AND PLATE FOR RAILWAY-SWITCH POINTS.

Application filed January 27, 1926. Serial No. 34,225.

This invention relates to a locking bar and plate structure adapted to be used in conjunction with the plunger of a switch operating mechanism and it consists in the novel 5 features hereinafter described and claimed.

An object of the invention is to provide a locking bar or member for railway switch points with a slot located at its edge and provided at the ends of the slot with recesses. Case-hardened lugs having angularly disposed end portions are provided and are adapted to fit snugly against the end edges of the slot and enter the recesses and completely fill the same whereby surfaces of 10 the lugs define end surfaces of the slots and other surfaces of the lugs lie in the same plane as those in which the side surfaces of the bar lie.

In the accompanying drawings:—

20 Figure 1 is a top plan view of a switch tongue operating mechanism having a plunger and with the locking bar and the plate connected with the switch mechanism and arranged to cooperate with the plunger.

25 Figure 2 is a side elevational view of the locking bar and plate and adjacent parts and showing one of the track rails and a switch point in section.

Figure 3 is an edge elevational view of 30 the locking bar and plate with parts broken away.

Figure 4 is a side elevational view of the same.

Figure 5 is a side elevational view of the 35 plate detached.

Figure 6 is a perspective view of the intermediate portion of the plate.

Figure 7 is a perspective view of one end portion of the locking bar.

40 Figure 8 is an enlarged transverse sectional view of the locking bar and plate cut on the line 8—8 of Figure 4.

Figure 9 is a detailed horizontal sectional view of a portion of the plate cut on the 45 line 9—9 of Figure 6.

Figure 10 is a perspective view of one of the lugs used upon the locking bar and the plate.

As illustrated in the accompanying drawings the switch operating mechanism is indicated at 1 and is provided with the usual plunger bar 2. The said operating mechanism is connected by means of a rod 4 with a switch tongue 5 located adjacent a track 55 rail 6 in the usual manner. A locking bar 7 is connected with the switch point 5 by

means of a cross bar 8. The bar 7 is threaded at its inner end as at 9 and nuts 10 are screwed upon the said threaded end and engage against the sides of an eye carried by 60 the cross rod 8 as best shown in Figure 1 of the drawings. The bar 7 is provided at its lower side and in the vicinity of its outer end with a slot 12 and at its upper side with a slot 13. The slots 12 and 13 do not register 65 with each other transversely of the bar. Angle lugs 14 are fixed against the end walls of the slots 13 and the said angle lugs are formed from case hardened metal as for instance steel and the lugs 14 are adapted to 70 receive one of the lugs 3 of the plunger 2 between them. The outer end of the bar 7 is threaded as at 15 and a plate member 16 is applied to the side of the bar 7 and is provided with a fork 17 which receives the 75 threaded portion 15 of the bar 7. Nuts 18 are screwed upon the threaded portion 15 and bear against the opposite sides of the fork 17 whereby the plate 16 is held at an adjusted position with relation to the lock 80 bar 7. A bolt 19 passes transversely through the intermediate portion of the bar 7 and through a slot 20 which is provided at the inner end of the plate 16. A nut 21 is 85 screwed upon the bolt 19 and bears against the side of the plate 16 whereby the said bolt and nut may assist in holding the plate at a fixed position upon the bar 7. The plate 21 is provided at one edge with a slot 22 and at its opposite edge with a slot 23. 90 Angle lugs 24 are fixed at the end of the slot 23 and are adapted to receive the plunger 2 between them. The lugs 24 are of the same form as the lugs 14 hereinbefore described and are made of case hardened material as for instance steel. The upper and lower edges of the lock bar 7 and the plate 16 register with each other and the lugs 14 95 are located at the opposite registering edges of the said parts from the edge thereof at 100 which the lugs 24 are located so that the lugs 14 receive between them the plunger 2.

The lugs 14 and 24 being of hard material prevent the parts from wearing and consequently the locking device is strong and 105 durable and will serve for a maximum length of time.

The lug 3 is part of the usual switch operating mechanism and it is carried by the usual plunger bar 2. The bar 2 passes transversely of the bar 7 and plate 16 which in turn are provided with recesses which receive 110

the lugs 14 and 24 and which constitute the subject matter of the present invention. The bar 7 and the plate 16 may be provided with any number of recesses and by shifting the plate with relation to the said bar certain of the said recesses may be brought into register with each other and when these recesses register the bar 2 is located in them. The present invention shows one method only of mounting and using the lugs 14 and 24 in recesses of a bar 7 and plate 16. The invention may be used to advantage in conjunction with other devices without departing from the spirit thereof as expressed in the claims.

13 Having described the invention what is claimed is:—

1. In a mechanism as described a bar member provided at its longitudinal edge with a slot and having at one side and at the 20 ends of the slots longitudinally disposed recesses and lug members of relatively hard material having angularly disposed end por-

tions, one end portion of the lugs bears against the end edges of the slot and the other end portions of the lugs entering the 25 adjacent recesses and completely filling the same.

2. In a mechanism as described, a bar member provided at its edge with a slot and at its side and at the end of the edge with a recess, a lug member of relatively hard material having angularly disposed end portions, one end portion of the lug being disposed transversely across the bar and with a surface in contact with the end edge of the slot, the other end portion of the lug member entering the recess and having surfaces in contact with the surfaces of the recess and completely filling the recess, said lug member having other surfaces which lie in the same plane as those occupied by the side surfaces of the bar member.

In testimony whereof I affix my signature.

GEORGE L. COWPERTHWAIT.
